UNITED STATES PATENT OFFICE.

RAFFORD PITT, OF NEW ROCHELLE, NEW YORK.

DOOR-HANGER.

1,229,653.

Specification of Letters Patent. Patented June 12, 1917.

Application filed May 4, 1915. Serial No. 25,682.

To all whom it may concern:

Be it known that I, RAFFORD PITT, a citizen of the United States, and a resident of New Rochelle, Westchester county, State of New York, have invented certain new and useful Improvements in Door-Hangers, of which the following is a specification.

This invention relates to improvements in door hangers.

10 By the use of my invention I am enabled to produce a door hanger preferably of the ball-bearing type which will not only be very light in weight, noiseless and inexpensive to manufacture, but will be free 15 from dust and dirt, consequently permitting the movement of a door to which it is attached with great facility, and said hanger will also have great rigidity and durability.

In the preferred embodiment of my invention which comprises a stationary member and a member movable relatively thereto, the stationary member is rolled from sheet metal to provide a track portion preferably with raceways for balls or other similar anti-friction devices, and has a securing portion in the form of a flange integral and preferably co-extensive with said track portion, said integral securing flange forming a shield against the admission of dust to the 20 raceways in the track portion of said stationary member and providing a flat securing surface for said stationary member, thus enabling the same to be secured at various points over the doorway, and adding rigidity to the structure without undue weight.

The movable member is also preferably rolled from sheet metal bent to provide a track portion with raceways registering with the raceways in the stationary member 25 to form channels to receive balls or other anti-friction devices and a securing portion in the form of a flange integral and preferably co-extensive with said track portion so as to provide a ready device for securing 30 the movable member rigidly and securely to the door and keeping out dust and dirt from the operating parts thereof, balls between the raceways in the movable and stationary members and ball-containers preferably comprising two abutting and connected strips of sheet metal ribbed longitudinally to afford rigidity and provided with ball-containing pockets formed by cutting spaced and registering apertures in 35 each of the abutting strips and "blistering" or bending the edges of the lower strip

downwardly and blistering or bending the edges of the apertures of the upper strip upwardly, whereby a pocket is formed for the balls.

In the accompanying drawings, in which similar reference characters designate corresponding parts throughout the several views,

Figure 1 is a side elevation of a portion of a door and doorway having the hanger embodying my invention applied thereto;

Fig. 2 is a side elevation of a portion of a door separated from the doorway, having the movable part of my hanger secured thereto;

Fig. 3 is a section on the line 3—3 of Fig. 1 illustrating my preferred form of hanger;

Fig. 4 is a section similar to Fig. 3 of a modified form of hanger embodying my invention;

Fig. 5 is an end elevation of the form of hanger illustrated in section in Fig. 3;

Fig. 6 is a view partly in section and partly in elevation of one end of a door to which my preferred form of hanger is connected, the stationary member which is attached to the wall being shown in section;

Fig. 7 is a plan view of the ball container preferably employed by me;

Figs. 8 and 9 are sections at right angles to each other of a ball pocket or ball seat in said container; and

Fig. 10 is a side elevation of a construction embodying a modified arrangement of the ball containers.

Referring now to Figs. 1 to 3 and 5 to 9 inclusive, 1 indicates the wall surrounding a doorway, 2 the stationary member of a hanger embodying my invention which is preferably of the cross-sectional form shown in Figs. 3 and 6 and comprises a track portion 2^a and a combined securing portion and dust shield 2^b provided along its length with suitable screw apertures to permit fastening thereof by screws 3 to the doorway. The said stationary member, as shown, is preferably co-extensive with the doorway and is preferably rolled up from a strip of sheet metal to provide intermediate the longitudinal edges of said strip, tracks or raceways 2^c, 2^d and 2^e respectively, terminating at one longitudinal edge in the flange 2^b which extends at an angle to said track portion, the other longitudinal edge being so disposed with relation to said flanged portion that when the said stationary member is secured,

to the doorway an entrance or operating slot 2^t will be provided to permit the reciprocation therein of the door connecting portions of the movable member hereinafter described.

The movable member 4 of the hanger also preferably comprises a track portion 4^a and flange portion 4^b which is preferably provided with suitable screw apertures and is 16 connected along the upper edge of the door by screws. Said movable member is, as shown, preferably co-extensive with the transverse edge of the door and is also preferably rolled up from a strip of sheet metal 15 to provide intermediate the longitudinal edges of such strip, tracks or raceways 4^c, 4^d and 4^e respectively which register with the tracks or raceways 2^c, 2^d and 2^e of the stationary member and one edge of said strip 20 terminates in the said securing flange 4^b which is of such conformation and is so disposed with relation to the stationary member as to extend through the slot 2^t and permit attachment of said track portion to the 25 door.

In Fig. 4 said securing flange is angular in conformation, Figs. 3, 5 and 6 illustrating the same as extending upwardly from the track-portion and thence outwardly through the slot 2^t and downwardly to the door where it is secured in any suitable manner.

In Figs. 3 and 5 said flange is shown as secured at one side of the door adjacent to 35 the top edge thereof, and in Fig. 6 as abutting against and secured to the top transverse edge of the door.

In Fig. 4 I have illustrated a hanger embodying a modified form of my invention 40 in which the stationary member is rolled up from a sheet of metal 10 to provide a track portion 10^a having longitudinal raceways 10^c—10^d and a securing flange 10^b at one longitudinal edge thereof, the opposite 45 longitudinal edge being so disposed in relation to said flange 10^b as to provide an operating slot 10^t. The movable member is also preferably rolled up from a single strip of sheet metal to provide a track portion 14 having ball raceways 14^a—14^b registering 50 with the raceways 10^c and 10^d of the stationary member to form ball channels therebetween, one longitudinal edge of said strip being bent to provide a flange 14^c to 55 permit the securing of the same in any suitable manner to the door.

In all the figures of the drawings I have illustrated balls 7 interposed in the ball channels formed between the longitudinal raceways of the stationary and movable members respectively and these balls are preferably seated in ball-containing pockets formed in ball containers 8 comprising two abutting and connected strips of sheet 60 metal 8^a—8^b, ribbed longitudinally to afford 65

rigidity and pierced with spaced apertures, the edges of which apertures are blistered or bent upwardly and downwardly as illustrated in Figs. 7, 8 and 9 to provide such pockets.

Separate ball containers are preferably provided for each set of balls. Thus in the construction shown in Figs. 3, 5 and 6, separate ball containers will be provided for the upper hold-down balls which are preferably disposed above the container for the lower or carrying balls and in the relationship shown in Fig. 1, namely, the ball-container for the carrying balls extends substantially three-quarters of the length of the stationary member and the containers for the hold-down balls extend substantially one-half of the length of the door which it is desired to hang, and is disposed centrally above the carrying-ball container.

Stops are also preferably provided at suitable points to prevent a creeping of the balls and as shown in said Figs. 1, 3, 5 and 6 stops 20 are attached by screws 20^a at each end of the stationary member and such stops close or seal up the ends of the said stationary member, thus adding to the dust-proof characteristics of the device. Stops 40 are also preferably provided at opposite ends of the door to limit the movement of the hold-down ball-container with relation to the carrying-ball container, so that during the continuance of such movement said container will always be in substantially the same disposition to the carrying-ball container, though both containers will change their positions relatively to the door and stationary member, and the said stops 40 are preferably of the configuration illustrated in Fig. 6 so as to limit the movement 100 of the hold-down ball-containers only while permitting free movement of the carrying-ball containers.

In Fig. 10, I have shown a construction in which the container for the upper or hold-down balls may be equal in length to the container for the carrying balls. In this construction, the stops 20 at the ends of the door or movable member may be omitted. Such an arrangement of containers is suitable for the construction shown in cross-section in Fig. 4, though it may be employed in the construction shown in cross-section in Figs. 3, 5 and 6. With said last mentioned arrangement of containers, however, the upper ball container or containers will project outwardly beyond and above the track portion of the movable member and though the movable member will in its movement pick up the balls one after another, a slight click or noise is likely to occur as such movable member comes into contact with the said balls. To obviate this, I preferably so magnetize the stationary member as to cause the same to become 110 115 120 125 130

permanently magnetic, and consequently the balls of the upper or hold-down ball-containers will be retained against the track or tracks below which such balls abut.

5 In other respects, the construction shown in Fig. 10 is similar to that illustrated in Fig. 1.

If desired, either of the constructions may be so magnetized and while such magnetizing of the track member will hold the balls against the respective tracks so that it will be unnecessary to connect the containers by a web or the like, it will have no effect upon the movement of such balls or 15 containers in relation to the tracks.

Another feature of my invention is the provision in a hanger of the type specified of a wiping element adapted to close the space between the stationary and movable 20 members and therefore keep out any dust from the movable parts, and also keep out cold air and drafts which are ordinarily admitted through the spaces between the parts of ball bearing door hangers.

25 Having described my invention, I claim:

1. A door hanger embodying a stationary member adapted to be secured to the wall of a building, and a member movable relatively thereto adapted to be attached to a 30 door, the stationary member comprising a strip of sheet metal bent to form intermediate the edges of said strip a track portion having ball raceways and an integral securing and dust-shielding flange at one longitudinal edge thereof, the other longitudinal edge being so disposed with relation to the securing flange as to provide an operating slot for the movable member, the said movable member also being provided with raceways registering with the raceways in the stationary member to form ball channels and balls suitably retained in said ball channels substantially as and for the purpose specified.

45 2. A door hanger embodying a stationary member adapted to be secured to the wall of a building, and a member movable relatively thereto adapted to be attached to a door, the stationary member comprising a 50 strip of sheet metal bent to form intermediate

the edges of said strip a track portion having ball raceways and an integral securing and dust-shielding flange at one longitudinal edge thereof, the other longitudinal edge being free and so disposed with 55 relation to the securing flange as to provide an operating slot for the movable member, the said movable member also being formed from a single strip of sheet metal bent intermediate its longitudinal edges to provide 60 longitudinal raceways adapted to register with the raceways in the stationary track portion to form ball channels, an integral securing flange at one longitudinal edge projecting through said operating slot and 65 connected to the door, and the opposite longitudinal edge of said movable member being free; said movable and stationary members having their secured and free edges extending in opposite directions, and balls 70 suitably retained within said ball channels.

3. A door hanger embodying a stationary member adapted to be secured to the wall of the building, and a member movable relatively thereto adapted to be attached to 75 the door, the stationary member comprising a single strip of sheet metal bent to provide a vertically-extending securing and dust-shielding flange, a horizontally-extending upper raceway, a vertically-disposed web 80 portion and a horizontally-disposed lower raceway; the movable member also comprising a single strip of sheet metal bent to provide a horizontally-disposed raceway, registering with the upper raceway in the stationary member, a vertically-disposed web portion, a horizontally-disposed raceway 85 registering with the lower raceway of the stationary member and a securing flange extending downwardly below said stationary 90 member, and balls suitably retained between the said raceways.

In witness whereof, I have signed my name to the foregoing specification in the presence of two subscribing witnesses.

RAFFORD PITTS.
